UNITED STATES PATENT OFFICE.

THOMAS J. PIERCE, OF PHILADELPHIA, PENNSYLVANIA.

COMBINED GAS AND ELECTRIC LIGHT FIXTURE.

SPECIFICATION forming part of Letters Patent No. 409,498, dated August 20, 1889.

Application filed June 19, 1888. Serial No. 277,582. (No model.)

To all whom it may concern:

Be it known that I, THOMAS J. PIERCE, a citizen of the United States, residing at Philadelphia, in the county of Philadelphia and State of Pennsylvania, have invented certain new and useful Improvements in a Combined Electric and Gas Light Fixture; and I do hereby declare the following to be a sufficiently full, clear, and exact description thereof to enable others skilled in the art to make and use the said invention.

This invention relates to fixtures for illuminating by gas-jets and by electricity, used either alternatively or simultaneously, and has for its object, by an improved construction of parts, the facilitating of the manufacture and the making of more substantial fixtures adapted to the masking of the electrical conductors and the protection of such conductors from injury by accident or from wear, and the convenient flexibility of the fixture without impairing the utility and convenience of the fixture for use in gas-lighting.

The nature of this invention consists in a surrounding metallic shell formed integrally with and braced by webs to each member of the flexible joints of the gas-fixture, inclosing an intervening chamber or conduit adapted to receive insulated electrical conductors required for lighting and support and protect the same without injury from flexure of the joints of the fixture, such joints being united by inner and outer tubes providing conduits for concealing and protecting the insulated conductors and for the passage of gas to the burner, as hereinafter fully described, and shown in the accompanying drawings.

Referring to the drawings, Figure 1 shows a side view of a flexible or swinging bracket-fixture containing this invention; Fig. 2, a vertical central section of a bracket with a swing-joint containing this invention; Fig. 3, a transverse vertical section of one of the swing-joints; Fig. 4, a detached view of one of the insulating-collars for guiding and protecting the electrical conductors through the joints, and Fig. 5 is a section in the plane indicated by the dotted line Z Z in Fig. 3.

50 The same letters of reference indicate the same parts in the several figures.

A represents the stationary member of a swing-bracket fixture, screw-threaded internally at the socket A' to fit the usual gas-pipe nipple, and having a stop-cock plug B fitting in a conical socket B', and the conical plug C of a swing-joint, fitting in a conical socket C'. A central tube A² extends centrally from the socket A' to the conical chamber C', where it terminates in a circular groove c². The outer shell A³ is cast with the tube A² and socket A', and conical sockets B' and C' with an intervening chamber A⁴, produced by coring in casting the part A. The upper part A⁵ of the space A⁴ surrounding the socket C' is open, leaving a circular space between the shell A³ at that point and the socket C' at that point. Apertures A⁶ lead through the shell A³ into the cavity A⁴.

The upper portion of the plug C is surrounded by a shell C², connected with the plug C by the tube C³, having a socket C⁵ at right angles thereto, all cast in one piece with the plug C, and having a chamber C⁴ between the tube C³ and shell C², open at the bottom C around the tube C³ and at the side C⁶ around the socket C⁵. The internal tubular parts of the joints are braced to the external shells by webs C⁷, one of which is shown in section in Fig. 5. These webs of metal serve to brace and stiffen the parts of the fixture so as to support the internal tube and hold it firmly to shape and position during the turning, drilling, and screw-threading required for finishing and fitting the parts, which would otherwise distort it, permitting an economy of material without impairing the strength. In the founding or casting operation the webs furnish a facility in making and placing the cores for producing the cavities or chambers C⁴. The location of the webs, as shown in Fig. 5, is such as to avoid abrading the insulated conductors. A collar D of electrical insulating material (shown detached in Fig. 4) fits in the openings A⁵ and C⁷, so as to turn therein with a bead D² between the parts. Through the collar D is a central hole D' for the passage of electrical conductors. The opening C⁶ is screw-threaded and has fitted in it a tube E, which surrounds, with an intervening space E', the tube F.

To the outer end of the tube E is attached

a chambered casting G, having in the center a socket G', formed therein and screwed to the tube F. The upper part of the socket G' is attached by a tube G² to the chamber G, all formed in a single casting by coring, with a space G³, having an opening G⁴ through a nipple G⁵ at the bottom, to which an incandescent electric-light bulb H is secured in the usual manner. The upper end of the tube G² terminates in a nipple G⁶, to which a gas-burner is applied. As shown in Fig. 1, an additional swing-joint is shown, the construction of which is the same as that shown in Figs. 2 and 3. The collar D serves to support the shell C² upon the shell A³, and, fitting the rim A⁵, materially strengthens the joint.

In use the gas passes from the pipe, on which the socket A' is screwed, through the tube A², being regulated or stopped by turning the plug B into the groove C³, enters the tube C³, passes thence through the tube F to the pipe G² upwardly into the burner J, whence it issues and burns. The electric wires K pass into the chamber A⁴ through the apertures A⁶, thence after being loosely coiled under the collar D in the chamber A⁴ around the socket C' upward through the central hole

D' in the collar D, thence through the space E to the chamber G³, and downwardly through the opening G⁴ into the electric-light bulb H. 30

It is obvious that the same arrangement and construction are applicable to chandeliers and other forms of gas and electric lighting fixtures.

Having described my invention and the 35 mode of making and operating the same, what I claim is—

1. In a combined gas and electric light fixture, the combination of the shells C² and A³, and the insulating-collar D, located in and between the said shells, with the plug C and gas-tube C³, substantially as shown and described, and for the purpose set forth. 40

2. In a combined gas and electric light fixture, the combination of the shell C², having a central gas-channel surrounded by an electric-wire channel, with the insulating-collar D, provided with the bead D², adapted to support the said shell, substantially as shown and described, and for the purpose set forth. 45

THOS. J. PIERCE.
